(57) CLAIM

The ornamental design for a log, as shown and described.

DESCRIPTION

FIG. 1 is a perspective view of a log showing my new design;

FIG. 2 is a front view thereof, the rear view being identical;
FIG. 3 is a right side view thereof; the left side view being identical;

FIG. 4 is a top view thereof;

FIG. 5 is a bottom view thereof;

FIG. 6 is perspective view of a second embodiment of my design;

FIG. 7 is a front view thereof, the rear view being identical;
FIG. 8 is a right side view thereof, the left side view being identical;

FIG. 9 is a top view thereof; and,

FIG. 10 is bottom view thereof.

The log is broken in the center to indicate indefinite length.

1 Claim, 4 Drawing Sheets

FIG. 2.
